(Cl. D85—2)

To all whom it may concern:

Be it known that I, Edward Leeberg, a citizen of the United States, residing at Roselle, in the county of Union and State of New Jersey, have invented a new, original, and ornamental Design for an Ash Tray or the like, of which the following is a specification, reference being had to the accompanying drawing, forming part thereof.

In the drawing:

Fig. 1 is a top view;
Figure 2 is a side or edge view, and
Figure 3 is a vertical section on line 3—3 of
Fig. 1, of an ash tray or the like showing my new design.

I claim:
The ornamental design for an ash tray or the like, as shown.

EDWARD LEEBERG.
